US0D1039358S

(12) **United States Design Patent** (10) **Patent No.:** **US D1,039,358 S**
(45) **Date of Patent:** **** Aug. 20, 2024**

(54) **STRAIGHT LATCH CAM**

(71) Applicant: **GEM Products LLC**, Jacksonville, FL (US)

(72) Inventor: **Jason Sarnowski**, Jacksonville, FL (US)

(73) Assignee: **GEM Products, LLC**, Jacksonville, FL (US)

(**) Term: **15 Years**

(21) Appl. No.: **29/813,028**

(22) Filed: **Oct. 26, 2021**

(51) **LOC (14) Cl.** **08-07**

(52) **U.S. Cl.**

USPC **D8/331; D8/354**

(58) **Field of Classification Search**

USPC D8/330, 331, 336, 339, 340, 341, 343, D8/349, 353, 354, 366, 384, 385; D12/223, 317

CPC E05B 2047/0024; B63B 17/00
